PACKAGE

Frank D. Palmer, Chicago, Ill., assignor to Seal-test, Inc., Baltimore, Md., a corporation of Maryland

Application July 1, 1940, Serial No. 343,383

3 Claims. (Cl. 229—23)

This invention relates to an improved package and more particularly to a package construction which is especially but not exclusively adapted to the packaging of products containing a considerable moisture content and which products are normally removed from the package in small quantities, the package being provided with a reclosable cover and of such a nature that it may remain in use for an extended period of time. A typical package of the kind indicated is a face cream package.

The main objects of the invention are to provide a package of the character indicated which will be of relatively simple construction but of attractive appearance so as to be well adapted to the packaging of such products as face cream; to provide a package which will be relatively strong and durable so as to be capable of extended use without loss of its attractive appearance; to provide such a package with an access opening affording convenient means for removing small quantities of the packaged material; to provide in such a package a closure which will effectively prevent evaporation of moisture or handling of the content of the package while on display, but which will afford visual examination of the package content; to provide a reclosable cover which will effectively protect and preserve the package content after the main closure has been removed; to provide a package construction of the character indicated which may be manufactured economically and at lowest cost and which may be shipped or stored prior to filling in knock-down or flat form; and in general it is the object of the invention to provide an improved package of the character indicated.

Other objects and advantages of the invention will be understood by reference to the following specification and accompanying drawing wherein there is illustrated a package embodying a selected form of the invention;

In the drawing:

Fig. 1 is a perspective illustrating the completed package;

Fig. 2 is a section on the line 2—2 of Fig. 1; and

Figs. 3, 4 and 5 are plan views of the respective elements employed in forming the improved package.

Referring now to the drawing, the improved package construction illustrated comprises three main elements, namely, a side wall forming member 6, a top wall member 7 and a bottom wall member 8.

The side wall member 6 comprises primarily an

elongated strip of paper board of suitable weight provided with suitable creasing, scoring or other fold lines extending transversely thereof as indicated at 9, such fold lines being provided, in this instance, to facilitate bending of the side wall strip 6 to form a hexagonal wall structure. As shown, the strip is divided by the score lines into seven substantially equal wall portions, one end wall portion completely overlapping the other end portion and being adhesively secured thereto to form the hexagonal body structure.

From one of the wall forming panels of the strip 6 there extends a cover forming flap 10, the same being of hexagonal form and adapted to fit within the hexagonal body formed as aforesaid. The cover member 10 is connected to the wall panel of the body strip 6 by means of a narrow strip 11, suitable score lines indicated at 10 being provided to permit folding or bending of the cover 10 and strip 11 relative to each other and relative to the side wall panel from which they extend. The cover 10 is also provided at one edge with a lip extension 12 which is foldable relative to the cover on a suitable score or fold line 13. The lip 12 is provided for the purpose of facilitating opening of the cover as will presently appear.

The bottom member 8 comprises a suitable paper board member cut to generally hexagonal form adapted to fit within the hexagonal wall member 6 and said bottom member is provided with peripheral flanges 14 which are foldable to laterally extending relation to the bottom wall along suitably formed fold lines 15 which divide the periphery of the hexagonal bottom member.

As best shown in Figure 2, the bottom member 8 is disposed within the hexagonal wall 6 and in upwardly spaced relation to the lower end of the latter. The peripheral flanges 14 of the bottom member are folded downwardly and occupy positions in face to face engagement with the respectively adjacent lower marginal portions of the side wall member 6. The flanges 14 and the adjacent portions of the side wall member 6 may be adhesively or otherwise secured together so as to permanently maintain the bottom member 8 in assembled relation to the side wall member 6.

The top wall 7 is also preferably formed of a suitable weight of paper board and it, like the bottom member, is provided with peripheral flanges 16 which are foldable relative to the top member along suitably provided fold lines 17 which divide the periphery of the illustrated hexagonal shape of said top member.

The top member 7 is provided with an open-

ing 18 through which access may be had to the content of the package and said opening is initially closed by means of a rupturable sheet of material 19. Said closing sheet 19 may be of suitable transparent material such as Cellophane, pliofilm or the like, and said sheet is of such size that marginal portions thereof extend beyond the edge of the opening 18 and such margin is preferably adhesively secured to the inside surface of the top member 7.

As best shown in Figure 2, the top member 7 is disposed within the hexagonal body 6 and in inwardly or downwardly spaced relation to the upper end of the side wall member. The peripheral flanges 16 of the top member extend outwardly or upwardly in face to face relation with the adjacent upper marginal portions of the side wall member and they may be adhesively or otherwise secured to said side wall member so as to maintain the top member in assembled relation to the side wall member.

The cover element 10 is adapted to be folded, as shown in Figure 2, downwardly into face to face engagement with the outside of the top member 7, the narrow hinge strip 11 permitting such positioning of the member 10. The lip 12 is of such dimension that it projects slightly beyond the upper edge of the side wall member 6 and thereby permits gripping thereof for facilitating withdrawal of the cover member 10. It will be observed that the cover member 10 fits snugly within the side walls 6 and within the flanges 16 of the top member 7. The fit of the cover 10 within said flanges is preferably of a snug character so that the cover 10 will be frictionally held in closed position.

Retention of the cover in closed condition is furthermore assisted by the illustrated hinge connection between the cover and the side wall member. It will be observed that the normal and inherent resiliency of the paper board stock from which the member 6 and cover 10 are formed causes the hinge strip 11 to tend to swing toward the center of the package and upwardly. Such tendency is translated into lateral or edge-wise movement of the cover 10, which consequently causes the lip bearing edge of the cover to bear with corresponding force against the adjacent wall or flange portion 16. The engagement between the lip bearing edge of the cover 10 and the flange 16 induced in the manner explained, adds substantially to the frictional retention of the cover in closed position but nevertheless offers no objectionable resistance to opening of the cover.

For packages containing a moisture bearing product, the side wall member 6 is preferably coated both on its inner and outer surfaces with paraffin, such coating being effected either before or after the member is formed into its hexagonal form. The top and bottom members 7 and 8 are also desirably coated with a moisture proofing material and paraffin may be employed for this purpose if desired. In connection with the employment of paraffin coatings, the various adhesively united parts may be united by the application of heat or pressure or both to effect fusion of the paraffin coatings on the respectively adjacent faces.

Bonds formed merely by fusing paraffin coatings are not entirely satisfactory in that they are not sufficiently secure. Therefore, the employment of another adhesive is desirable. According to the present invention, the use of a separate adhesive for joining the various parts

with the employment of the necessary apparatus for handling such adhesive is eliminated by applying to the inner surfaces only of said top and bottom members 7 and 8 a coating of a suitable rubber or latex and paraffin, or wax composition, many of which are commercially available, wherefore specific explanation of the composition appears unnecessary. Such compositions, due probably to their rubber content, provide much better adhesive properties than wax or paraffin alone and they have the ability to mix or fuse with paraffin.

When the top and bottom members 7 and 8 are coated on their inside surfaces with the said rubber-wax composition, the corresponding faces of the flanges 16 and 14, respectively, are also coated with such material. Hence, when the top and bottom walls are assembled with the side wall member 6, the rubber-wax coatings on the respective flanges 16 and 14 engage the paraffin coating on the respectively adjacent side wall portions of the member 6. By the application of heat or pressure or both, the contacting coatings may be effectively fused so as to produce an entirely satisfactory bond between the parts.

For joining the overlapping wall panel portions of the side wall member 6, the paraffin coatings alone may be relied upon, or, as preferred, other adhesive may be employed and the member formed into hexagonal form before applying the paraffin coating. If, however, it is preferred to coat the side wall member 6 before forming it into the band-like member, some of said rubber-wax composition may be applied between the overlapping wall panels to produce a satisfactory adhesive connection therebetween.

In a package structure formed as explained, the paraffin coatings on the side wall member provide adequate moisture proofing for said side wall member and impart to the same a desirable glossed appearance which adds to the attractiveness of the package. The paraffin coating is, of course, also applied to the cover forming part 10 so that when the package is displayed the side walls and the top wall member, whether open or closed, disclose the same wax-polished appearance as the side wall member. The wax-rubber coatings on the inside surfaces only of the top and bottom members provide adequate moisture proofing therefor.

The rupturable closure 19 may be secured to the inside of the top wall 7 merely through the agency of said wax-rubber coating, suitable heat or pressure or both being applied to effect such union, or, if preferred, other adhesive may be employed for this purpose.

The described package structure may be shipped from the manufacturer to the user in unassembled flat form embodying the relatively independent side wall member and top and bottom wall sections, or, if preferred, the carton manufacturer may form the side wall member into an endless band by joining the end panel sections thereof in the manner already explained. When the side wall member 6 is initially formed into an annular band, it may nevertheless be shipped in flat condition by collapsing such band to flat form by folding the same on an oppositely disposed pair of fold lines 9 as will be readily understood by those skilled in the art. The equipment required for assembling and adhesively uniting the various parts is obviously of very simple character so that no great expense is required in connection with such assembly.

The packages may be filled from either end prior to the assembling of the corresponding end with the side wall member and it will be understood that the heat required (if any) for effecting the fusion of the adhesive coatings is not sufficient to impair the package content.

The described package structure is advantageous not only because of its simple but attractive character, but also because it eliminates relatively difficult adhesive applying and handling operations. Furthermore, the major portion of the package area is moisture proofed by employment of relatively inexpensive paraffin (as compared with considerably more expensive wax-rubber composition) so that the cost of the moisture proofing is maintained very low.

I am aware that changes in the described structure may be made without departing from the principles of the invention, the scope of which should be determined by reference to the following claims, the same being construed as broadly as possible consistent with the state of the art.

I claim:

1. A package of the character described comprising an annular side wall member, a bottom wall disposed within said side wall member and spaced upwardly from the lower end thereof, said bottom wall having peripheral flange portions depending therefrom in face to face engagement with the adjacent lower marginal inside portions of said side wall member and secured thereto, a top wall formed independently of said annular side wall member, disposed within said side wall member and spaced downwardly from the upper end thereof, said top wall having peripheral flange portions extending upwardly therefrom in face to face engagement with the adjacent upper marginal inside portions of said side wall member and secured thereto, said top wall having an access opening therein, and a reclosable cover for the package comprising a member hingedly connected to a portion of said side wall member and frictionally fitting within said upwardly extending top member flanges, and a lip extending outwardly from a portion of said cover opposite to said hinge connection for facilitating removal of said cover.

2. A package of the character described comprising an annular side wall member, a bottom wall disposed within said side wall member and spaced upwardly from the lower end thereof,

said bottom wall having peripheral flange portions depending therefrom in face to face engagement with the adjacent lower marginal inside portions of said side wall member and secured thereto, a top wall formed independently of said annular side wall member, disposed within said side wall member and spaced downwardly from the upper end thereof, said top wall having peripheral flange portions extending upwardly therefrom in face to face engagement with the adjacent upper marginal inside portions of said side wall member and secured thereto, said top wall having an access opening therein, a rupturable closure for said opening secured to the inside of said top member around said opening, and a reclosable cover for the package comprising a member integrally hingedly connected to the upper end of said side wall member and frictionally fitting within said upwardly extending top member flanges, and a lip extending outwardly from a portion of said cover opposite to its said hinge connection with said side wall member for facilitating removal of said cover.

3. A package of the character described comprising a tubular body member of multi-sided form, the inner surface of said body member being coated with paraffin, top and bottom end members corresponding in shape to the multi-sided form of said body and of such size as to fit snugly within the same, said end members having peripheral flanges extending outwardly therefrom in face-to-face relation to inside marginal end portions of said body, said end members, including their peripheral flanges, having a coating of a wax-rubber composition, said wax-rubber coating being on the flange faces which contact the body member, the inter-engaging coated areas of said body member and end members being adhesively united by fusion of said coatings, said top member being provided with an opening affording access to the interior of the package, and a closure for said opening comprising a flap corresponding in shape to the multi-sided form of said body and of such size as to fit frictionally within the outturned peripheral flanges of said top member and against the outside thereof, means hingedly connecting said closure flap and one of the walls of the body, and a lip extending from said cover flap opposite to said hinge connection for facilitating opening and closing of the cover.

FRANK D. PALMER.
